US00D664652S

(12) **United States Design Patent**
Hermle

(10) **Patent No.:** **US D664,652 S**
(45) **Date of Patent:** **** Jul. 31, 2012**

(54) **atrium retractor**

(75) Inventor: **Rainer Hermle**, Gosheim (DE)

(73) Assignee: **Karl Storz GmbH & Co. KG** (DE)

(**) Term: **14 Years**

(21) Appl. No.: **29/394,975**

(22) Filed: **Jun. 23, 2011**

(30) **Foreign Application Priority Data**

Dec. 23, 2010 (EM) 001798331-0005

(51) **LOC (9) Cl.** **24-02**

(52) **U.S. Cl.** **D24/135**

(58) **Field of Classification Search** D24/135;
128/846; 600/201, 208

See application file for complete search history.

(57) **CLAIM**

The ornamental design for an atrium retractor, as shown and described.

DESCRIPTION

FIG. 1 is a front perspective view of an atrium retractor in accordance with the new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof; and,
FIG. 7 is a bottom plan view thereof.
